BLACK-OUT SYSTEM

Peter Hinshelwood, Chicago, Ill.

Application January 30, 1942, Serial No. 428,921

16 Claims.

(Cl. 179—2)

My invention relates to a novel electrical system or circuit and the object thereof is to provide novel means for operating or controlling an electrical circuit and equipment, machinery or other load therein by the operation of another circuit, such as a telephone or like communication system or circuit, and especially the call or signal circuit thereof, without electrical connection or interference with the latter circuit, but only, solely and purely by mechanical operation, intervention or interposition of a controlling means for the first circuit from the signal circuit thereof without requiring a response or answering of the signal or call such as by lifting the receiver of a telephone or responding orally thereto and without drawing on the current or electrical circuit connecting with the second circuit such as a telephone or like call or communication circuit or system.

Another object of the invention is to provide a black-out system or control for a lighting circuit to turn the same on or off at any desired time, or whenever the emergency should arise or be terminated, merely by calling a telephone number or substation, preferably known only to those in authority for such purposes or emergencies and merely by the use of switches in connection with the controlled circuit or circuits operated mechanically by calling said numbers, preferably two, one for opening the circuit, and the other for closing the circuit so controlled for causing a black-out or turning off the lights and then turning on the lights, respectively.

A further object of the invention is to provide means for controlling an electrical circuit and its equipment, such as a lighting circuit by means of another or controlled circuit, such as a telephone circuit, whereby the first circuit may be rendered operative or inoperative, as desired, over a prescribed or predetermined section, area, building, home and equipment therein, or independently of the telephone circuit by other operating means.

Another object of the invention is to provide an electrical control system or circuit whereby a communicating system, such as a telephone circuit, may be used to mechanically operate a switch at a substation upon calling said substation, subscriber or a certain and preferably secret telephone number known only to those having charge thereof, so that upon the operation of the signal circuit, or call bell thereof, a switch or controlling means for a lighting or other separate circuit will be mechanically operated such as by movement of the signal, buzzer or call bell hammer, striker, clapper or metal bell ringer

tongue to operate a switch controlling the operation of said lighting or other separate circuit in which it is included.

Another object of the invention is to provide a system of electric circuit control whereby upon calling or signaling a certain number or subscriber known only to a proper authority, the movement of the signal bell clapper thereof may be used to mechanically close a normally open switch positioned adjacent or in juxtaposition thereto for directly or indirectly completing or closing an electrical circuit for a lighting system or having other current consuming devices, or for directly completing a circuit for the lighting system of a building or area, machinery or other load therein, and by calling another number or subscriber, will similarly operate another but normally closed switch to open the circuit thereof for directly or indirectly opening the circuit of said lighting system or included current consuming devices, machinery or load therein, so that the system is adapted, among other purposes and uses, for blackouts of different areas and buildings and for relighting or re-establishing the controlled circuit or circuits, as desired, such as after a predetermined period or when the danger is passed.

Another object of the invention is to provide a holding means for holding the circuit closed when certain telephone number is called or signalled to close a switch controlling a lighting or other circuit, so that said circuit will remain closed when completed; for as long a period as desired, or, until another telephone number is called to operate or open another controlling switch to open said circuit and extinguish the lights or render the load therein inoperative, or to release a switch, gravity or otherwise operated, to normally and automatically open a circuit controlling said lighting system or load.

A still further object of the invention is to employ the striking power or physical movement of the hammer or metal tongue of the bell ringer of a signal of a telephone set, the result of the magnetization of the solenoids of the signal circuit thereof to close a normally open momentary contact switch to close a magnetic circuit which closes the main switch or contactor of a consuming circuit or controlling switch thereof to allow current to flow to a motor for operating a large or giant oil switch controlling a lighting circuit or other energy consuming devices. On the other hand, when it is desired to open the circuit and stop the motor or current from flowing to any of the current consuming devices or

units, the striking power of the standard telephone bell ringer metal tongue is again used to open a normally closed momentary contact switch by calling a second telephone number, but without electrical connection with the telephone circuit or use of any of the telephone company's internal electric connections, interference with or taking any current therefrom, the operative connection being purely mechanical by the movement of the bell ringer.

Another object of the invention is to provide a system of electric circuit control so that the operation of the circuit or the control of the circuit mechanism such as lighting or black-out, may be effected at any time from any point near or far, and irrespective of the distance where a local or long distance telephone in the system is accessible or available, instead of only at fixed or set intervals unless manually changed or requiring an attendant, or involving expense thereof, such as where controlled by clock or clock actuated switches, and altered by manual intervention where weather conditions change or alter the times when it is necessary or desirable to turn on or off the lights, as often happens, and which requires personal attention or manual intervention of an attendant.

Another object of the invention is to provide a circuit control system which may be used in conjunction with the usual clocks for controlling or operating switches for turning the lights on or off, or permitting the elimination of the clocks and the expenditures incident to their use and maintenance, and which permits or makes use of a telephone system or circuit, or other communicating system already established throughout, whereby the lighting may be turned on or off at any point from any other point near or remote therefrom, and which may be economically and easily installed simply by removing one of the bells located in the call box of the signal circuit of a telephone set or substation and installing the necessary switch to be actuated thereby in conjunction with the controlling circuit, so that the device will be dependable and in position for operation at all times.

Another object of the invention is to provide means for automatically causing a black-out or turning off a section of a lighting system, such as a city, area, building, or home, or for turning the same on, merely by calling two different telephone numbers, call stations or substations, one for turning the lights on, and the other for turning off the lights, by introducing two switches adjacent the telephone signals or call boxes for mechanical operation, but without electrical connection or affecting the communication or signal circuits of the telephone system.

Other objects and advantages will appear and be brought out more fully in the following specification.

Fig. 1 is a diagram of a system of electric circuit control in accordance with the invention and showing a two pole single throw contactor switch and two telephone call stations with switches, one of which is normally open, and the other of which is normally closed;

Fig. 2 is a similar view, but showing all of the switches closed;

Fig. 3 is a similar view, but showing all of the switches open;

Fig. 4 is detailed view showing the manner of mounting the switches adjacent to the call box of a telephone for operating the same;

Fig. 5 is an enlarged fragmentary elevation

showing the manner of mounting the switch, but taken at right angles to Fig. 4.

Fig. 6 is a diagrammatic view similar to Fig. 1 but showing the circuit connected to an oil switch operated by a motor wound spring and clock controlled as well as a solenoid controlled switch; and

Fig. 7 is a view showing three positions of the clock controlled switch.

10 Referring to the drawings in detail, 10 and 11 designate the line wires supplying current from a suitable source in the ordinary 110 volt supply circuit, or the like, leading to the conductors 12 and 13 connected to a lighting circuit in which a suitable load, machinery or current consuming devices or units may be connected and illustrated by a motor 14 interposed in the circuit to operate certain equipment, but which motor may be employed to operate an oil or other giant switch controlling a circuit of considerably greater voltage and load which may control the lighting system of a large building, city, area, or section thereof. This motor may be used to wind the spring of a large electric oil switch which controls the lighting of a boulevard or other area or machinery. Interposed in the supply lines 10 and 11 leading to the conductors or lines 12 and 13 may be a suitable switch 15 conventionally illustrated as a two pole single throw contactor switch having the blades or movable contacts 16 and 17 connected as at 18 to move in unison and normally opened by gravity, or otherwise with respect to the contacts 19 and 20, with which they cooperate to close the circuit. This switch may be operated magnetically or otherwise, but is shown connected as at 21 with a magnetic core operated by an electro-magnet or relay 22 which, upon being energized, will close the switch, and which, upon being de-energized, will release the switch to permit the same to automatically open by gravity or otherwise, as previously pointed out. A thermal overload 23 may be included in the line 13 for the purpose of protecting the circuit and the motor or other equipment or current consuming devices or units therein which may be a lighting system or in which the motor may be employed for opening and closing oil switches or other means of controlling a circuit of high voltage, amperage or wattage, such as the lighting circuit of a building, boulevard or other area, as normally done in practice at the present time, or otherwise, such as synchronous clocks.

In order to control the closing and opening of the switch 15 and the circuit thereof, which may be a house lighting circuit of 110 volts, or otherwise, or the motor 14, or other device which controls an oil switch or suitable means for controlling a circuit of higher voltage or tension for controlling the lighting of a large building, boulevard or other area, city or section thereof, such as 600 to 1000 or 2000 or more volts, a normally open switch 24 and a normally closed switch 25 preferably of the momentary contact type or a snap switch which may be of a type such as shown in Patent No. 1,960,020, dated May 22, 1934, are positioned adjacent or in juxtaposition to the signal or call boxes 26 of two telephones comprising the usual set, including a signal or call box, receiver and transmitter of the two subscribers' lines or substations 27 and 28 of a telephone system, which, for convenience, may have the numbers Lights 2222 and Black-out 3333, respectively. Each box houses a signal or call mechanism of the respective telephone numbers, 75 which have, or are operated by magnetic signal

circuits, including electric magnets or solenoids 29 and 30 operating an oscillating or pivoted armature 31 having a hammer, striker, clapper or bell ringer 32 with a spring metal tongue and ball adapted to strike and sound a pair of bells, one of which is removed or omitted for the purposes of the present invention, but without preventing the signal or buzzer from sounding on the other bell. Otherwise, the telephone set is the same as normal and undisturbed to operate in the usual manner for telephone conversations or outgoing calls, unless the signal is operated to ring the other bell in accordance with the present invention on an incoming call, as will be later described. The line or return 11 is connected by a conductor 34 to one terminal or binding post of the normally open switch 24 and the other terminal or binding post thereof is connected by a conductor 35 to one terminal or binding post of the normally closed switch 25. The supply or lead line 10 is connected around the switch 15 by a conductor 36 to one end of the coil or winding of the electro-magnet or solenoid 22, with an interposed mechanical thermal unit or thermal cut-out 37 forming a circuit breaker which operates on an overload in the circuit by or from the thermal overload 23 to break the circuit to the electro-magnet 22 so that the same will be de-energized and release the switch 15 to normally open and prevent damage. The other or opposite end of the coil of the electro-magnet or solenoid 22 is connected by a conductor 38 to the other terminal of the normally closed switch 25. In addition, a third conductor 39 extends from the terminal of the switch blade 17 to the conductor 35 for completing a circuit through either one or both of the switches 24 and 25 under certain conditions, as will be hereinafter explained. It may also be mentioned that each one of the switches 25 and 26 has an upwardly extending arm or lever 40 which is positioned adjacent one side of each striker 32 wherever the particular numbers may be located at adjacent or distant points relative to each other, but they may be located in the same home or building or at a power station closely adjacent one another or at the same office where a person or persons having charge of the system may be located. For this purpose, a slot 41 may be provided in the bottom of each call box 26, openings being generally provided therein for the purposes of ventilation, cooling, and to render the signals more easily audible.

Operation

In the operation of the system, assuming that the switch 15 is normally open by the deenergization of the operating magnet 22 and the switch 24 open while the switch 25 is closed, if it is desired to close the circuit to the motor 14, or lights therein or controlled thereby or to other machinery, equipment or current consuming devices or units, such as for the purposes of turning on the lights of a building or area before or after a black-out, an authorized person lifts the telephone at his desk, or any telephone in the local or long distance system, and calls the number Lights 2222 at the particular locality in which the system is installed, either through an operator or automatic dial system. When the connection is made, the magnets or solenoids 29 and 30 of the particular number or signal device 27 thereof are energized to operate the striker 32 and may signal the bell 33, or the latter may be omitted entirely. This movement of the striker 32 causes it to en-

gage the arm or lever 40 of the normally open switch 24 and by a slight movement mechanically operate the latter to close the same to complete the closing circuit through the electromagnet 22 to energize the same and close the switch 15, thus turning on the lights therein or controlled thereby, such as by means of the motor 14 which may operate a suitable oil switch or the like of sufficient capacity according to the area or section being controlled, such as a city, section thereof, boulevard system, or other lighting unit, machinery or load. In this instance, the circuit is traced from the lead 10 to the conductor 36 through the thermal unit 37, magnet 22, conductor 38 through the normally closed switch 25, conductor 35 through the momentarily closed switch 24, which, as before stated, has been closed by the striker 32 engaging the arm or lever 40, and then through the conductor 34 to the line wire 11. The switch 24 will, however, immediately return to a normally open position to break the closing circuit, but the switch 15 will be retained in a closed position by the holding circuit which is completed by the closing of the switch 24. This holding circuit is traced from the lead 10 through the conductor 36 and thermal unit 37 to the magnet 22 and then through the conductor 38 and switch 25 to the conductor 35 with the return through the conductor 39 and line 11 through the switch blade 17 which has been momentarily closed through the closing of the switch 24 and will remain closed with the switch 15 so that the lights or power will remain in the circuit directly controlled by the switch 15 for as long as desired. Ordinarily, this circuit is controlled by a clock controlled switch which may be omitted or used in conjunction with the present system, if desired. The usual difficulty with such clock controlled switches is that weather conditions vary, and if set for certain times to close and open a lighting circuit, darkness may come on from a storm, and there will be no lights, or, the light of the day may come on before or later than the time set, or darkness may come on earlier or be delayed, so that operation of the switch or circuit controlling the lights will have to be affected manually in order to meet the particular circumstances, and the cost of installation and maintenance thereof is considerable, if not excessive. The telephones for operating the present circuit, while mainly intended to be called in the usual way, may be automatically actuated in any suitable manner at stated intervals or certain times, but it is preferable to operate the same as described, to suit particular conditions such as conditions of weather, or particularly for the purpose of turning on the lights or causing a black-out and the cost of installation and maintenance is practically nil, or very low. For the purpose of a better understanding of the switches 24 and 25, it may also be explained that these switches are made in both normally open and normally closed form, and the ones diagrammatically illustrated each consist of a contact arm operatively mounted so that its free end moves between two stops or contacts and the arm usually comprises a thin leaf spring of very thin beryllium, Phosphor bronze, a copper strip or ribbon, or other metal operatively supported at one end in cantilever fashion, the other end being free to move. The strips or stops are preferably of silver or other metal to minimize damage resulting from arcing during the making and breaking of an electrical circuit, and therefore the switch is of the snap type with but slight movement of the arms or

levers 40 required to close or open the same, and, of course, this is momentary by the operation of a striker 32 of the signal, after which the switch will return to its normal position in which the switch 24 is open and the switch 25 is closed.

As before stated, the circuit including the switch 15 when operated to turn on the lights and close the circuit through the switch 24 from the position shown in Fig. 1 of the drawings, will cause the completion of the circuit as shown in Fig. 2 of the drawings when the holding circuit is effective. Therefore, when it is desired to again open the circuit, such as for turning off the lights during a black-out, such authorized person merely calls the other telephone number, such as Black-out 3333 and, upon connection being made by the operator or automatically with the dial system, the striker 32 of the signal device 28 thereof engages the arm or lever 40 of the normally closed switch 25, and by striking the same, momentarily opens the holding switch and breaks the circuit to the electro-magnet 22, thereby permitting the switch 15 to automatically open, as by gravity due to the deenergization of the electro-magnet 22. This circuit will remain open as long as desired to extinguish the lights or break the circuit to the motor 14 or lights controlled thereby, or to other current-consuming devices. The closing of the circuit may be completed merely by again calling Lights 2222, as previously described, and while the telephone system is used to control the operation thereof, no current is taken from the telephone line nor any electrical connection made therewith, as the operation of the switches 24 and 25 is purely mechanical from the strikers 32, while the telephone system operates in the usual way, and all that is necessary is to mount the switches 24 and 25 in proper relation to the telephone signal boxes 27 and 28 in the circuit controlling the operation of the switch 15, and this may be the present clock operated circuit in which the present system is installed in conjunction with the clocks, but preferably to take the place thereof with the additional advantages referred to above, including the important fact that the circuit may be operated to extinguish or turn on the lights at any time for a black-out or according to variable weather conditions and meet all possible exigencies which may occur, as well as being capable of operation locally or at any distance wherever a telephone is accessible.

In Fig. 6 of the drawings, the conductors 12 and 13 are extended to an electro-magnet or relay 42, the core 43 of which operates a normally open relay or switch 44, shown opened by a spring 45. The movable contact 46 in one position engages a pair of spaced stationary contacts 47 and 48, and in another position, engages similarly spaced stationary contacts 49 and 50. A clock operated three-way contact switch 51 has a blade 52 pivoted at 53 and cooperating with contacts 54 and 55 with an intermediate neutral position. A three-way mechanically reversed switch 56 is connected in circuit for operation by the motor 14, one terminal thereof leading to the pivot point 57 of a movable contact blade 58 which cooperates with spaced contacts 59 and 60 in different positions of the switch blade, while the intermediate position is neutral. The contacts 54 and 59 are connected by a conductor 61, and the contacts 55 and 60 are connected by a conductor 62 with the contacts 49 and 50 interposed and forming a gap therebetween adapted to be closed by the movable contact 46 operated by the relay or

electro-magnet 42. The contacts 47 and 48 are connected to the pivot terminal 53 of the switch blade 52 and the contact 54, respectively, and the other side of the motor 14 is connected by a conductor 63 to the line wire 11. The terminal 53 is connected by a conductor 64 to the line wire 10 with an interposed lock switch 65 manually opened when working on a high voltage circuit, or otherwise suitably operated.

Fig. 7 shows the circuit through the switches 51 and 56 open. The clock operated switch 51 is set to open and close the circuit at stated intervals, such as to close the same at 6 p. m. and to open the same at 6 a. m., by way of example, and therefore, will not operate at other times, this being taken care of by calling the telephone numbers for turning the lights on or off in the manner previously described in connection with Figs. 1, 2 and 3 of the drawings, and therefore the operation thereof is not repeated at this time. The three-way mechanically operated switch 56 is mechanically reversed when the oil switch is operated by the motor 14, the motor serving to wind a spring which, upon reaching a certain tension, is automatically released to reverse the position of the switch blade 58, as is common in this type of switch. In Fig. 7, the switches 51 and 56 are shown closed to complete the circuit to the motor in the lefthand position when the lights go on at 30 6 p. m., while the intermediate position shows the switch is open after the lights have been turned on after 6 p. m., the switch blades having been advanced 180 degrees after each movement to contacting position and in the third or righthand position, the position of the switches is shown open at 6 a. m., when the lights are turned off. In Fig. 6, the conductors 12 and 13 are shown extended for connection with a solenoid or electro-magnet 66 where only a solenoid controlled switch is used. In each instance, it is understood that the movable contacts of the solenoid operated switches are moved into one position when the electro-magnets are energized, and automatically move to another or open position when the electro-magnets are de-energized, and this movement in all of the switches is made quickly to avoid arcing. The movable contact 67 of the solenoid controlled switch having the electro-magnet or solenoid 66 cooperates with contacts 68 and 69 controlling the circuit, including conductors 70 and 71, so that when the circuit is closed at the electro-magnet 66, the armature or core thereof will be attracted to close the circuit across the contacts 68 and 69. In view of the foregoing, it is thought that the operation of the device will be readily understood, and it will be seen that it takes care of all possible conditions with high or low voltage, since the conductors 63 and 64, instead of being connected to the line wires 10 and 11 may be connected to any supply circuit of any desired voltage, according to the purpose for which the operating circuit is used, and at the amperage required, but operated with the clock switches stationary.

It will thus be seen that lights or other electrical equipment may be turned on or off at any time desired, notwithstanding the condition of the operating circuit or the setting of the clocks operating or controlling the oil switches for turning the lights on or off or controlling the lights or other electrical apparatus or equipment, so that the lights or such apparatus or equipment may be turned off at any time desired irrespective of the position of the clocks. Thus, the lights may be turned off earlier in the mornings or on

later in the evenings if day light comes on earlier or persists later. Thus, saving considerable in the cost of lighting and correspondingly in the operation of other electrical apparatus or equipment.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variation and modifications as come within the scope of the appended claims.

Having thus described my invention, what I claim as new and desire to secure by Letters Patent is:

1. In a system of electric control, the combination with a power circuit having current consuming units and a switch for controlling said circuit, of a communication circuit electrically independent of said power circuit and having a pair of signal means for each call station each with a different call number, and means mechanically actuated by one of said signal means for causing actuation of said power circuit switch to close said circuit, and means mechanically actuated by the other signal means for causing actuation of the switch to open the circuit.

2. An electrical circuit control system comprising the combination with an electric communication circuit having a call means and a movable element operable upon actuation of the call means, of an operating circuit normally open, means for closing said latter circuit, and means in another circuit mechanically operated only by said movable element upon actuation of the call means to affect the operation of said closing means for the operating circuit.

3. An electrical circuit control system comprising the combination with an electric telephone circuit having a call device with a movable element, of an operating circuit normally open, means for closing said circuit, another circuit for electrically operating said closing means and means in the latter circuit operated mechanically by the movable element upon operating the call device to open or close said circuit last named said telephone circuit being electrically independent of the other circuits.

4. The combination with a telephone communication circuit, of a power circuit unconnected to the telephone circuit and having normally open control means, said telephone communication circuit having a signal means identified by certain call indicia with a movable element and another circuit independent of the telephone circuit for operating said control means to open or close the same and the circuit controlled thereby, including a switch operated by said movable element upon operating said signal means.

5. A communication circuit having a pair of associated call means each having a movable signal element identified by different call indicia, in combination with a power circuit electrically unconnected to the communication circuit, a circuit closer in said power circuit, a circuit electrically connected to said power circuit and including means to open said circuit closer when one of said call means is actuated and to close said circuit closer when the other of said call means is actuated.

6. The combination with a communication circuit having stations, of a power circuit having

control means, said stations of the communication circuit having each a signal means with a movable element and another circuit for operating said control means to open or close the same and the circuit controlled thereby, said third circuit including a switch positioned to be physically operated by said movable element upon operating the signal means of different stations without electrical intervention or connection with said communication circuit.

7. An electrical circuit control system comprising the combination with an operating circuit for controlling lights or other equipment and having a normally open switch means electrically operated for controlling the same, of a telephone circuit having call stations each with the usual signal device including a striker, a circuit for operating said control device including actuating means therefor, and switches positioned to be operated by said strikers upon movement of the latter to momentarily effect said controlling circuit to close said normally open switch means and to release the same to close and open the operating circuit respectively.

8. In a system of electric circuit control, the combination with a power circuit and a normally open switch in said circuit; of an operating circuit having means for closing said switch, a pair of signal devices included in a telephone circuit, a normally open switch in said operating circuit adjacent the signal operator of one device and a normally closed switch in the telephone circuit adjacent the signal operator of the other signal device, to momentarily close or open the circuit through said switch closing means.

9. In a system of electric circuit control, the combination with a power circuit and a normally open switch in said circuit; of an operating circuit having means for closing said switch, a pair of signal devices included in a telephone circuit, a normally open switch in said operating circuit adjacent the signal device operator to be closed upon actuation of the signal device operator adjacent thereto and a normally closed switch in the operating circuit adjacent the signal device operator of the other signal device to be opened upon the actuation of the signal device operator adjacent thereto for closing and opening said power circuit respectively, said latter switches being free of electrical connection with the telephone circuit.

10. The combination with a power circuit such as a lighting circuit, having electrical means of opening and closing the same, of a control circuit including said means, and having separate normally open and normally closed switches for closing and opening said control circuit, and adapted to be mechanically operated by the signal devices of two telephones of a telephone system for closing and opening the circuit to the electrical means of the power circuit for closing and opening the latter respectively.

11. The combination with a power circuit such as a lighting circuit, having electrical means of opening and closing the same, of a control circuit including said means, and having separate normally open and normally closed switches respectively for closing and opening said control circuit, and adapted to be solely mechanically operated by the signal devices of two telephones of a telephone system upon calling the same to close the normally open switch upon calling one telephone to close the power circuit and to open the normally closed switch to open the power circuit upon calling the other telephone,

and a holding circuit including said means, closed by closing said control circuit at one of said switches through the other of said switches and opened by opening the last named switch.

12. The combination with the electrical circuit, of a communication system having signal devices with a movable part for each call station; of a power circuit, a normally open switch in and controlling the power circuit, a control circuit including electrical means for closing said switch, a holding circuit also including said closing means to hold said control circuit closed, and movable means adjacent a signal device operated wholly physically by a movable part to close the control circuit upon operation of the signal device to close the holding circuit and movable means adjacent another signal device operated wholly physically by another movable part to open the control and holding circuits to permit the first switch to open.

13. The combination with the electrical circuit, of a communication system having signal devices for each call station; of a power circuit, a normally open switch in the power circuit, a control circuit including electrical means for closing said switch, a holding circuit also including said closing means, a normally open momentary contact switch positioned adjacent one signal device for purely mechanical operation thereby to momentarily close the control circuit to close the first switch and holding circuit to maintain the last named switch closed upon calling the phone having said signal device, and a normally closed momentary contact switch positioned adjacent another signal device for similar purely mechanical operation thereby to momentarily open the control circuit at such point and also open the holding circuit to release the closing means of the first switch and permit the latter switch to open the power circuit.

14. The combination with a telephone circuit and signal devices of substations therein having strikers, an operating circuit including a normally open switch, a working circuit having clock

operated switches and a control circuit including an electro-magnetic device for closing said open switch, a holding circuit therefor, and a pair of contact switches, one normally open and

5 the other normally closed and connected to each other so that the holding circuit is completed by closing the open contact switch while the other is closed, said pair of switches each having an operating arm in juxtaposition to the striker of a signal device for operation thereby.

15. In a system of electrical circuit control, a power circuit constituting an operating circuit, a normally open switch in said circuit for controlling the same, a communication circuit having 15 at least two independent calling stations each with a call device having a movable element, a normally closed switch having an actuating part adjacent the movable element of one call device, a normally open switch having an actuating part adjacent the movable element of the other call device for opening and closing the switch controlling the power circuit free of electrical connections with the communication circuit, a holding circuit established by the closing 25 of the circuit to the control switch and opened by the opening of the second normally open switch to open and close said power circuit.

16. The combination with a telephone circuit and signal devices of substations therein having strikers, an operating circuit including a normally open switch, a working circuit having time controlled switches and a control circuit including 30 an electro-magnetic device for closing said open switch, a holding circuit therefor, and a pair of contact switches, one normally open and the other normally closed and connected to each other so that the holding circuit is completed by closing the open contact switch while the other switch is closed and the holding circuit is opened 35 by opening the latter switch and releasing the closed but normally open contact switch to permit the same to open.

PETER HINSHELWOOD.
